US00D967170S

(12) **United States Design Patent** (10) **Patent No.:** **US D967,170 S**
(45) **Date of Patent:** **** Oct. 18, 2022**

(54) **PORTION OF A DISPLAY SCREEN WITH A GRAPHICAL USER INTERFACE**

(71) Applicant: **Hoffmann-La Roche Inc.**, Little Falls, NJ (US)

(72) Inventor: **Kevin Adam Stewart**, Dundee (GB)

(73) Assignee: **Hoffmann-La Roche Inc.**, Little Falls, NJ (US)

(**) Term: **15 Years**

(21) Appl. No.: **29/831,083**

(22) Filed: **Mar. 17, 2022**
